FLASH IGNITION PLUG FOR GAS ENGINES

Filed Dec. 5, 1925

INVENTOR.

BY *M. J. Dikeman*

ATTORNEY.

UNITED STATES PATENT OFFICE

MYRON J. DIKEMAN, OF DETROIT, MICHIGAN

FLASH IGNITION PLUG FOR GAS ENGINES

Application filed December 5, 1925. Serial No. 73,459.

The object of my invention is to produce a flash ignition plug that will ignite the fuel gas within the cylinder of an engine, when under compression, by means of flames shooting from the small ports in the side of the plug walls, throughout the engine cylinder gas, causing a thorough combustion in all sections of the engine cylinder simultaneously, instead of at only one point as is the case 10 with the ordinary spark plug now in common use.

Another object is to produce an automatic flash plug, provided with internal mechanical means for filling the plug flash chamber with 15 gas directly from the engine cylinder chamber on the compression stroke of the engine, and to automatically discharge all burned gases left in the plug chamber directly into the engine cylinder chamber as the engine 20 exhaust valve is opened.

A further object of my invention is to produce a flash ignition plug, so designed and protected that oil and grease from the engine cylinder cannot enter or affect the operation 25 and efficiency of the ignition spark therein.

A still further object is to produce an ignition flash plug having a multiplicity of ignition points provided therein, and so arranged that new points may be brought into action 30 by turning of a projecting rod attached thereto.

These several objects are attained in the preferred form by the construction and arrangements more fully hereinafter set forth.

Similar parts on all drawings are marked 35 by similar numerals.

Fig. 1 shows the exterior of my device ready for attaching to the engine cylinder.

Fig. 2 is a top view of the flash plug showing the relative position of the exterior parts.

Fig. 3 is a sectional view of the plug, taken on the line —AA— of Fig. 2, showing the general arrangement of the working parts and their relation to each other.

Fig. 4 is a sectional view taken on the line —BB— of the Fig. 3, showing the firing disc and electric spark terminal point, and the means for insulating the point from the cylinder walls.

Fig. 5 is an alternate view taken on the

same line —BB— of the Fig. 3, showing the firing disc with a multiplicity of firing points and the means for insulating same from the plug casing.

Fig. 6 is a detail view of the piston plug 55 showing a separate firing disc of different material attached to the bottom thereof.

Fig. 7 is an alternate form for closing the lower end of the plug, by the use of a head socket screwed thereon and having the flash 60 port holes in the bottom of the socket walls.

I will now describe more fully the detailed construction of my flash plug, referring to the drawings and the marks thereon.

In general, my device comprises a hollow 65 plug casing having a cylindrical firing chamber therein, practically closed at the bottom end thereof, except for small port holes through the end chamber walls, and is provided with external threads for screwing the closed end into a plug opening of an engine 70 cylinder head, so as to project the small end ports within the engine cylinder. Within the cylindrical firing chamber is placed a closely fitted piston, free to slide to the bottom end 75 of the plug chamber under the pressure of an engaging coil spring placed above the piston, and arranged to recede against the spring pressure, upward against a valve seat, when subjected to the compression of the engine cylinder gas, communicated thereto

through the small end ports in the end plug walls, thus allowing the plug firing chamber to fill with gas directly from the engine cylinder. Electric ignition spark points having an insulated member are mounted within the plug firing chamber, having means for connecting same into an electric circuit, for igniting the gas within the plug chamber 80 and causing flames to shoot from the bottom port holes of the plug for igniting the engine cylinder gas. Upon the opening of the engine exhaust the pressure within the plug chamber is also lowered, and the coil spring 85 forces the piston to the bottom of the plug chamber, and discharges therefrom all burned gases, leaving the plug chamber ready for a new filling of fresh gas on the compression stroke of the engine.

The plug casing —1— is made of metal suit- 100

able for withstanding heat, without undue expansion, and as a matter of convenience, is formed with an external hexagon collar —2— near the bottom end of the casing as a means for screwing the plug into a cylinder-head of an engine. Below the collar —2— and adjacent thereto is formed a threaded section —3— for engaging and screwing into the engine cylinder head opening ordinarily provided therein for an engine spark plug now commonly used in most types of gas engines. The plug casing —1— is formed with a true cylindrical chamber —5— through nearly the entire length thereof, and is closed at the bottom end thereof by the end cap —4— projecting from the threaded end section —3—. Small port holes —6— are formed through the end walls —4—, and the threaded section being of sufficient length to project the end —4— and ports —6— just inside the engine cylinder head wall. The small ports —6— may be formed in the end wall, or the side wall, or in both end and side walls as shown in Fig. 3, providing small communicating passages between the engine cylinder and the cylindrical chamber —5— of the plug. The top end of the metal plug casing —1— is fitted with the end cap —7—, preferably attached thereto by threaded walls. The cap —7— is formed with a central slide bearing —8— positioned concentric with the axis of the cylindrical chamber —5—. Also through the walls of the cap —7— are formed air vent holes —9— to allow the passing of air as the piston —10— slides within the cylindrical chamber —5—. The piston —10— is a metal cylindrical plug, closely fitted to the walls of the chamber —5—, forming as nearly an air tight joint therewith as possible and allow the piston —10— to slide freely therein. The piston —10— is provided with a slide rod —11—, projecting therefrom along the axis of the piston, engaging the bearing —8— in the cap —7—, for guiding and holding the piston —10— in a true position within the cylindrical chamber —5—. Also fitted tightly within the top end of the chamber —5— is a tubular piston seat thimble —12—, forming an air tight joint with the chamber walls —5— and providing an air tight end joint when engaged with the piston —10— as the piston is forced to its upper position under the pressure from the engine cylinder, and acting as a valve seat for the piston and forming an air tight firing chamber at the lower end of the chamber —5—. The thimble —12— being of a length to position the piston at approximately the center of the cylinder when the piston is raised in contact therewith. The purpose of the thimble —12— is to provide a simplified means of forming a shouldered seat for the piston and making an air tight joint therewith, and which could likewise be formed by turning a

shouldered seat directly on the cylinder walls —5—, making the two pieces as one solid piece. A coil spring —13— is mounted on the slide rod —11—, within the thimble —12— engaging the piston —10— and the cap —7—. The action of the coil spring —13— forces the piston —10— to the bottom of the cylindrical chamber —5—, in a position as shown in Fig. 1 of the drawings, when the piston —10— is not under pressure from the engine cylinder. The piston —10— is free to slide therein under the action of the coil spring —13— and the pressure from the engine compression. The piston —10— is preferably formed with a sharp lower edge, formed by a narrow end groove intersecting the side piston wall, leaving the lower edge wall sharp, and for the purpose of scraping and cleaning the side walls of the chamber —5— and keeping same free from carbon deposits resulting from combustion of the gases. At the bottom end of the piston —10— is formed a circular pointed star firing disc —15—, the circumference being positioned concentric with the axis of the piston, and of a diameter slightly less than the diameter of the inclosing cylinder —5—, so the sharp circumferential teeth of the firing disc lie near the cylinder walls but not in contact therewith. The firing disc —15— may be turned directly on the piston body from the same piece of metal, or a separate disc —16— may be attached thereto as shown in Fig. 6, should it be desirable to make the firing disc of a different material. The operation is the same in either case. Through the wall of the plug casing —1— positioned directly opposite the edge of the firing disc —15— when the piston —10— is resting in its upper position is mounted an electric spark terminal pin —17—, positioned therein so that the inner end of the pin lies near the sharp circumferential points of the firing disc —15—, but not in contact therewith or projecting beyond the chamber walls —5— to interfere with the movement of the piston —10—. The terminal pin —17— is thoroughly insulated from the plug casing —1— by the insulator plug —18— tightly fitted and sealed in the casing walls. The outer end of the terminal pin —17— is provided with means for attaching the end of an electric circuit wire —22— thereto for placing the terminal pin and firing disc —15— in an electric circuit with any battery. The piston plug and attached firing disc being grounded with the engine frame as is usually the case, completes an electric circuit, and which will cause a spark to pass between the inner end of the terminal pin —17— and the point nearest the pin end of the firing disc —15—, when the electric circuit is closed through the engine commutator or distributing head as the engine piston reaches the upper position of the compression stroke, and which compres-

sion is also thereby communicated to the plug chamber —5—, through the small ports —6— in the lower end of the plug casing, and forcing the piston —10— to its firing position at the top of the chamber, seating against the end of the thimble —12— and forming an airtight chamber. As the piston —10— raises in the cylinder —5—, the air above the piston easily escapes through the small air ports —9— in the cap —7—. At the firing point of the engine cylinder, an electric spark is passed between the terminal pin —17— and firing disc —15—, igniting the gas which has been forced in the plug chamber —5— by the compression of the engine cylinder, and causing flames to emit from the small port holes —6— in the bottom end of the plug, and shoot throughout the engine cylinder fuel gas chamber, igniting the entire mass, simultaneously, instead of at only one point as is the case with the ordinary spark plug now in common use for this purpose. Upon the lowering of the engine cylinder pressure, at the exhaust portion of the engine stroke, the pressure in the plug chamber is likewise released, and the coil spring —13— then forces the piston —10— to the bottom of the cylindrical chamber —5— and forces all burned gases out of the plug chamber, and ready for re-filling the chamber —5— with a fresh charge of gas from the engine cylinder at the compression stroke of the engine.

Fig. 4, illustrates a terminal pin —17— with but a single sparking point thereon, while Fig. 5, illustrates a terminal pin —17— having a multiplicity of points on the inner end of the pin, all arranged concentric with the firing disc —15—, the teeth being of a smaller pitch than those of the firing disc, and affording range for the passing of an electric spark therebetween, in case some of the adjacent disc points become inoperative. The piston —10— may be turned within the cylinder —5—, as desired, for bringing new disc firing points opposite the point of the terminal pin —17—.

An alternate form of my plug is shown in the Fig. 7, the plug being exactly the same as shown and described heretofore, except the bottom end —4— is omitted as cut on the line —CC— in Fig. 3, leaving the lower end of the plug chamber —5— open, and then screwing the plug casing —1— into a special head socket —19— which has formed therein special ports —21— through its closing end —20—. The socket —19— is screwed into the engine cylinder head in the same manner as the original plug, operating in the same manner, but less efficient as there is a small amount of dead gas which the piston —10— cannot expel therefrom.

I do not wish to be confined to the exact construction of my flash plug as herein shown and described, as it is evident there are numerous mechanical designs for accomplish-

ing the above results, and therefore claim all flash ignition plugs that are substantially a substitution of parts herein shown.

Having fully described my flash ignition plug, what I claim and desire to secure by Letters Patent is:

1. A flash ignition plug adapted for igniting the fuel gas of a gas engine, by a flash flame, comprising a hollow metal plug casing having a true cylindrical chamber formed therein closed at the bottom end of said plug except for small port holes formed through the end walls, external threads formed near the lower end of said plug casing, above the end port holes and positioned to project the plug end and ports just inside the wall of an engine cylinder head when said plug is screwed therein, a slideable piston mounted inside said cylindrical chamber, means attached to said sliding piston to force same to lower end of the chamber near the end port holes, electric spark points mounted within said cylindrical chamber for causing a spark therein when the piston is in its upper position in said chamber, and means for connecting said spark points in an electric circuit.

2. A flash ignition plug adapted for igniting the fuel gas in the cylinder of a gas engine, by a flash flame, comprising a hollow metal plug casing having a true cylindrical chamber formed therein extending nearly the entire length of the plug casing, said chamber being closed at the bottom end of the plug except for small port holes formed through the end walls, external threads formed on the outer wall of the plug casing, above and adjacent to the end port holes, positioned to project the end of the plug and port holes just inside of the wall of an engine cylinder head when said plug casing is screwed therein, a movable piston fitted within said cylindrical chamber designed to recede from the port end of the plug when the said piston is subjected to air pressure entering through the small port holes, spring means attached to the piston for forcing same back to the port end of said plug casing when the engine air pressure is removed from the cylindrical chamber, and means installed within said plug chamber to cause an electric spark therein when the piston has receded to its upper position.

3. A flash ignition plug adapted for igniting the fuel gas in the cylinder of a gas engine, by a flash flame, comprising a tubular metal plug casing, closed at the bottom end except for small port holes through the end casing walls, said tubular casing being formed with a true cylindrical wall inner chamber, and having external threads formed on the bottom end thereof positioned to project the plug end and ports just inside the wall of an engine cylinder head when the plug casing is screwed therein, a movable pis-

ton fitted within said cylindrical chamber and free to slide therein, an end cap attached to the upper open end of the plug casing, spring means mounted within said cylinder above the said piston for engaging and forcing the piston to the bottom end of the chamber near the end ports, firing contact points projecting from the bottom side of the piston and positioned near the inclosing cylinder wall, an electric contact point mounted in the side wall of the plug casing and duly insulated therefrom, said contact point being positioned directly opposite the firing point on the bottom of the piston when the piston is at the upper position in said cylinder and means for connecting the points in an electric circuit.

4. A flash ignition plug adapted for igniting the fuel gas of a gas engine, by a flash flame, comprising a hollow metal plug casing having a true cylindrical chamber formed therein extending nearly the entire length thereof and closed at the lower end of said casing except for small port holes through the end casing walls, external threads formed on the outer wall of said plug casing, above and adjacent to the small ports, so positioned as to project the closed end and small ports inside the wall of an engine cylinder when the plug casing is screwed therein, a metal end cap fitted and attached to the top end of the casing, said cap having air ports formed therein, a sliding piston mounted within the cylindrical chamber free to slide to the bottom port end of said chamber, a seating piston thimble mounted above the piston to form an air tight joint therewith when said piston is at its upper part of the stroke, a compression coil spring placed above the piston so as to force said piston to the lower port end of said cylinder, a firing disc formed on the bottom of said piston, an electric terminal pin mounted in the casing wall, thoroughly insulated therefrom and positioned to lie opposite the edge of the piston firing disc when said piston is resting in its upper position, and means for connecting said terminal pin to an electric wire.

5. A flash ignition plug adapted for igniting the fuel gas in the cylinder of a gas engine, by a flash flame, comprising a metal plug casing having a true cylindrical chamber formed lengthwise therein, said chamber being closed at the lower end thereof except for small port holes through the end walls of the casing, means for attaching said casing in a plug hole of an engine cylinder head, a true cylindrical piston with slide attached, closely fitting said cylinder walls installed within said cylinder, said piston free to slide therein and is provided with a sharp lower edge for scraping the cylinder walls clean, a tubular piston thimble fitted in the top end of the casing cylinder chamber, above the piston, positioned to engage said piston at

about the center of the cylindrical chamber and form an air tight seat therewith, a cap attached to the top end of the plug casing and extending across the open end thereof, a compression coil spring inserted within said cylinder between the cap and the piston for forcing said piston to the bottom of the chamber, firing points attached to the bottom of the piston and positioned near the cylinder walls, an electric terminal pin mounted through the casing wall, thoroughly insulated from said casing and positioned so its inner end lies near and directly opposite the firing points on the bottom of the piston when the piston is in its upper position within said cylinder, and means for connecting an electric wire to the outer end of said terminal.

6. A flash ignition plug adapted for igniting the fuel gas in the cylinder of a gas engine comprising a hollow metal plug casing having a true cylindrical chamber formed lengthwise therein, said chamber being closed at the bottom end of said casing except for small ports through the end casing walls, exterior threads formed on the lower end of said casing, above and adjacent to the small ports, so positioned as to project the small ports just inside the wall of an engine cylinder when the plug casing is screwed therein, an end cap fitted and attached to the upper open end of said casing and provided with a central slide bearing therein, a cylindrical piston truly fitted to the walls of the cylindrical chamber but free to slide therein, said piston having a projecting slide extending from the top side thereof and engaging and sliding within the central cap bearing, a tubular piston thimble tightly fitted into the top end of the cylindrical chamber, above the piston and positioned to engage the piston at about its central position within the cylinder chamber and form a tight end joint with said piston, a compression coil spring mounted on said central slide and engaging the piston and cap for forcing said piston to the bottom of the chamber, air ports arranged in the top end of the cylinder above the piston, said piston being formed with a sharp lower perimeter edge and a projecting firing disc beneath the sharp perimeter edge, an electric terminal pin fixedly mounted in the side wall of the casing and insulated therefrom by a sealed insulating plug and so positioned in the casing wall as to bring the inner pin point directly opposite the edge of the firing disc when the piston is raised against the engaging piston thimble, and means for attaching an electric wire to the outer end of said terminal pin.

7. A flash ignition plug adapted for igniting the fuel gas within the cylinder of a gas engine, by a flash flame, comprising a tubular casing with one closed end except for small port holes through the closed end walls,

means for attaching said casing within the hole through the wall of a cylinder head, a movable piston fitted within said tubular casing free to slide therein, a spring attached to the top of said piston to force it to the bottom of the tubular chamber, two electric spark points thoroughly insulated from each other mounted inside the cylinder under the piston when in its upper position, and means for passing an electric spark between said spark point.

8. A flash ignition plug adapted for igniting the fuel gas in the cylinder of a gas engine, by a flash flame, comprising a metal plug casing having a cylindrical chamber formed lengthwise therein, said chamber being closed at the lower end except for small port holes through the closing end walls, a piston fitted within said cylindrical chamber and free to slide therein, a piston seat projecting from the cylinder walls for engaging the piston at about its central position in the cylinder and making same air tight, means attached to the piston for forcing same to the bottom of the cylinder casing, a firing disc attached to the bottom of the piston and projecting therefrom, an electric terminal pin mounted through the casing walls opposite said firing disc when the piston is in its upper position in said cylinder, said terminal pin being fully insulated from all metal parts adjacent thereto.

In witness whereof I sign these specifications.
